US00D703711S

(12) **United States Design Patent**
Andrews et al.

(10) **Patent No.:** **US D703,711 S**
(45) **Date of Patent:** **** Apr. 29, 2014**

(54) **VENTILATED VACUUM COMMUNICATION
STRUCTURE**

(71) Applicant: **Curt G. Joa, Inc.**, Sheboygan Falls, WI (US)

(72) Inventors: **Robert E. Andrews**, Sheboygan, WI (US); **Jason Hohm**, Sheboygan Falls, WI (US)

(73) Assignee: **Curt G. Joa, Inc.**, Sheboygan Falls, WI (US)

(**) Term: **14 Years**

(21) Appl. No.: **29/465,046**

(22) Filed: **Aug. 23, 2013**

(51) LOC (10) Cl. **15-09**

(52) U.S. Cl.

USPC **D15/138**

(58) **Field of Classification Search**

USPC D15/199, 138; 83/100; 156/73.1, 250, 156/256, 265; 198/374, 417, 803.13; 221/1; 226/43, 118; 242/58.3

See application file for complete search history.

(57) **CLAIM**

We claim the ornamental design for a ventilated vacuum communication structure, as shown and described.

DESCRIPTION

FIG. 1 is a perspective view of a ventilated vacuum communication structure;

FIG. 2 is a first side view of the ventilated vacuum communication structure;

FIG. 3 is a second side view of the ventilated vacuum communication structure;

FIG. 4 is a top view of the ventilated vacuum communication structure;

FIG. 5 is a bottom view of the ventilated vacuum communication structure;

FIG. 6 is a front view of the ventilated vacuum communication structure; and,

FIG. 7 is a rear view of the ventilated vacuum communication structure.

CERTIFICATE OF CORRECTION

PATENT NO. : D703,711 S
APPLICATION NO. : 29/465046
DATED : April 29, 2014
INVENTOR(S) : Andrews et al.

Page 1 of 1

It is certified that error appears in the above-identified patent and that said Letters Patent is hereby corrected as shown below:

On the title page, item (56) Other Publications insert -- "Reciprocating Mechanisms", Franklin Jones,
Vol. 1, date unknown, 2 pages --

Signed and Sealed this
Thirtieth Day of September, 2014

Michelle K. Lee
Deputy Director of the United States Patent and Trademark Office
